RUBBER THREAD

John R. Gammeter, Akron, Ohio, assignor, by
mesne assignments, to United States Rubber
Company, New York, N. Y., a corporation of
New Jersey

Application August 24, 1933, Serial No. 686,583

17 Claims.

(Cl. 18—8)

This invention relates to the manufacture of rubber thread and to a method for the continuous and rapid production of such thread in a simple and inexpensive manner from a suitable rubber-containing fluid such as a solution or dispersion of rubber or rubber-like material.

Other advantages will readily appear from the following description, reference being made to the accompanying drawings, in which:

10 Figs. 1a, 1b, and 1c are side elevations of the apparatus, bottom, mid and top sections, respectively, the apparatus being arbitrarily divided into three sections in the drawings for facilitating the illustration thereof;

15 Fig. 2 is a detail side elevation showing the apparatus for applying the rubber-containing fluid to the traveling wire.

Fig. 3 is a cross sectional view of the traveling wire; and

20 Figs. 4a and 4b are front elevations of the apparatus, bottom and top portions respectively, the apparatus being arbitrarily divided into two sections in the drawings for facilitating the illustration thereof.

25 According to the invention, a rubber-containing fluid, preferably an aqueous dispersion of rubber or rubber-like material, is applied to the surface of a travelling wire having at least one comparatively sharp longitudinal edge, and the rubber is deposited from the dispersion onto the 30 surface of the wire by a drying operation, which may be preceded by a chemical coagulation of the rubber, if desired. The rubber deposit is stripped off the travelling wire in thread form, 35 the deposit being divided along the sharp edge or edges of the wire by the stripping operation. If a wire having only a single sharp longitudinal edge is used, a single thread which will be hollow and slit longitudinally will be formed. If a flat ribbon-like wire is used, two threads, one from each 40 face of the ribbon, will be formed. A triangular wire, as shown in the illustrations, will produce three threads, one from each flat face thereof, and in like manner an increase in the number of sharp edges above three will produce a corresponding increase in the number of threads.

45 Such threads formed on a flat face of a ribbon wire, or triangular wire, or the like will be lens shaped in cross-section more exactly plano-con-
vex. The rubber-containing fluid is preferably a latex containing vulcanizing ingredients, and preferably contains a low temperature accelerator so that the rubber may become vulcanized during the drying operation prior to stripping 50 from the wire. So called vulcanized latex may be used if desired. The latex is preferably concentrated by an evaporation, or a chemical or a mechanical creaming process, as is well known in the art.

55 60 Referring to the drawings, illustrating a pres-

ent preferred apparatus for carrying out the invention, an endless triangular wire 10 travels under a drum 11 driven by a motor assembly 12, and over a second drum 13, parallel to the drum 11. The drums 11 and 13 have a series of parallel circumferential grooves across the width thereof shaped to fit the travelling wire, and the wire is fed from one groove of the bottom drum to the corresponding groove of the top drum and then around the next groove of the bottom drum, 10 and then top drum, and similarly across the width of the drums, where the wire is fed with the help of pulleys 14 and 15 back to the starting groove of the drums.

The lower surface of drum 11 is immersed in a 15 tank of coagulant 16 so that the wire may be wet with coagulant before passing through the latex 17 in tank 18 shown in detail in Figure 2. The various passes of wire wet with coagulant 20 are wiped by means of a wiper 19 at the bottom of the tank 18 through which the wire enters the latex bath, the wiper also acting to prevent the downward flow of latex through the aperture in the bottom of the tank.

The wire leaves the tank 18 and passes through 25 a vertical drying chamber 20, (see Figures 1a and 1b) entering at 21 and leaving at 22, hot air for the drying entering at 23 and leaving at 24, to be returned to the fan, washer and heater (not shown) and to be recirculated at 23. The wire 30 leaving the drier at 22 with the dried rubber deposit, preferably vulcanized, passes through a talcer 25 and the rubber deposit is removed from each face of the wire in the form of a thread by take-off rolls 26, 27 and 28 rotated by means of 35 a small motor assembly 29 and the necessary pulleys and belts. The thread T as stripped from the travelling wire is fed to thread containers 30.

As shown in Figures 4a and 4b there are as 40 many passes of wire as there are grooves in the surface of drums 11 and 13 and if one deposit of latex gives a rubber film of sufficient thickness, the take-off rolls 26, 27 and 28 may pull off threads from each pass of the endless wire. If desired, the threads may be stripped from 45 every other pass of wire, in which case the threads will be correspondingly heavier since formed by a double deposition process. In like manner, threads may be stripped off from every third or fourth pass of wire, and so on. It has 50 been found advantageous to apply coagulant prior to the coating with latex but if desired the coagulant bath 16 may be omitted entirely.

In operation, as may be clearly seen from the 55 drawings, each pass of the wire 10 is fed through the coagulant bath 16, through the latex bath 17, where a film of latex is coagulated on the wire, through the drier 20 where the coagulum is dried and preferably vulcanized, and then through the talcer 25. The threads are stripped off each face 60

- of whatever passes of the travelling wire may be desired, by means of pull off rolls 26, 27 and 28 and then fed to appropriate thread containers 30, or other collecting means.
5. As various modifications other than those suggested herein will occur to those skilled in the art, it is not intended to limit the invention other than as set forth in the appended claims.
- Having thus described my invention, what I claim and desire to protect by Letters Patent is:
1. The method of making rubber thread comprising depositing rubber from a rubber-containing fluid onto a travelling wire having at least one comparatively sharp longitudinal edge and stripping the rubber deposit from the wire surface in thread form.
  2. The method of making rubber thread comprising depositing rubber from a rubber-containing fluid onto a travelling wire having at least one comparatively sharp longitudinal edge whereby the rubber will deposit thinly over said edge and be easily divisible therealong, and dividing the rubber deposit along said edge and stripping the same from the wire surface in thread form.
  3. The method of making rubber thread comprising depositing rubber directly from an aqueous dispersion of rubber onto a travelling wire having at least one comparatively sharp longitudinal edge and stripping the rubber deposit from the wire surface in thread form.
  4. The method of making rubber thread comprising depositing rubber directly from an aqueous dispersion of rubber onto a travelling wire having at least one comparatively sharp longitudinal edge whereby the rubber will deposit thinly over said edge and be easily divisible therealong, and dividing the rubber deposit along said edge and stripping the same from the wire surface in thread form.
  5. The method of making rubber thread comprising applying an aqueous dispersion of rubber onto the surface of a travelling wire having at least one comparatively sharp longitudinal edge, drying the deposit on the wire, and stripping the dried rubber deposit from the surface in thread form.
  6. The method of making rubber thread comprising applying an aqueous dispersion of rubber onto the surface of a travelling wire having at least one comparatively sharp longitudinal edge whereby the rubber will deposit thinly over said edge, drying the deposit on the wire, and dividing the rubber deposit along said edge and stripping the same from the wire in thread form.
  7. The method of making rubber thread comprising chemically coagulating a coating of an aqueous dispersion of rubber on the surface of a travelling wire having at least one comparatively sharp longitudinal edge, drying the coagulum on the wire, and dividing the dried deposit along the edge and stripping the same from the wire in thread form.
  8. The method of making rubber thread comprising depositing rubber from a rubber dispersion onto a travelling wire having a plurality of comparatively sharp longitudinal edges, whereby the rubber will deposit thinly over said edges and comparatively thickly over the other portions of the surface, and dividing the rubber deposit along said edges and stripping a plurality of
  9. The method of making rubber thread comprising applying an aqueous dispersion of rubber onto the surface of a travelling wire having a plurality of comparatively sharp longitudinal edges, drying the deposit on the wire, and dividing the dried deposit along said edges and stripping a plurality of threads from the portions of the surface between said sharp edges.
  10. The method of making rubber thread comprising chemically coagulating a coating of an aqueous dispersion of rubber on the surface of a travelling wire having a plurality of comparatively sharp longitudinal edges, drying the coagulum on the wire, and dividing the dried deposit along said edges and stripping a plurality of threads from the portions of the surface between said sharp edges.
  11. The method of making rubber thread comprising applying an aqueous dispersion of rubber onto the surface of a travelling triangular wire, drying the deposit on the wire, and stripping off the dried rubber from the faces of the wire between the edges thereof to form rubber thread.
  12. The method of making rubber thread comprising depositing rubber from a rubber dispersion on the surface of a travelling triangular wire whereby the rubber will deposit thinly over the sharp edges thereof and comparatively thickly over the faces thereof, and dividing the rubber deposit along said edges and stripping off the rubber in thread form from the faces between said edges.
  13. The method of making rubber thread comprising coagulating an aqueous dispersion of rubber on the surface of a travelling triangular wire, and stripping the coagulum from the faces of the wire between the edges thereof in thread form.
  14. The method of making rubber thread comprising chemically coagulating an aqueous dispersion of rubber on the surface of a travelling triangular wire, drying the coagulum on the wire, and stripping the dried deposit from the faces of the wire between the edges thereof in thread form.
  15. In an apparatus for making rubber thread, a travelling wire having at least one comparatively sharp longitudinal edge, means for applying a rubber-containing liquid coating material onto said wire, means for drying said material, and means for stripping off the dried rubber deposit in thread form.
  16. In an apparatus for making rubber thread, a travelling triangular wire, means for applying a rubber-containing liquid coating material onto said wire, means for drying said material, and means for stripping off the dried rubber deposit from each of the three faces of the wire in thread form.
  17. In an apparatus for making rubber thread, a travelling wire having a plurality of faces and comparatively sharp longitudinal edges between said faces, means for applying a rubber-containing liquid coating material onto said wire, means for drying said material, and means for stripping off the dried rubber deposit from the faces of the wire between the edges thereof in thread form.

JOHN R. GAMMETER.
